UNITED STATES PATENT OFFICE.

WILLIAM H. DONALD, OF CINCINNATI, OHIO, ASSIGNOR TO THE F. A. KNOWLES SLICER COMPANY, OF CINCINNATI, OHIO, A CORPORATION OF OHIO.

SLICING MACHINE.

Application filed December 14, 1923. Serial No. 680,652.

To all whom it may concern:

Be it known that I, WILLIAM H. DONALD, a Canadian subject of the King of Great Britain, residing at Cincinnati, in the 5 county of Hamilton and State of Ohio, have invented certain new and useful Improvements in Slicing Machines, of which the following is a specification.

My invention relates to machines for 10 slicing meat and other edibles, in general, and more particularly to the kind disclosed and claimed in my Patents No. 1,362,855, dated December 21, 1920 and No. 1,437,145, dated November 6, 1923, upon which the 15 present invention is an improvement.

Its object, like those inventions, is to make such a machine simple of construction, convenient to use and to keep clean, and reliable and accurate in operation and not 20 readily deranged in its use or by tampering. An object peculiar to the present invention is to permit the ready release of the carrier from its driving mechanism at the end of feeding, and, preferably, to effect 25 this release automatically. A further object is to provide for ready adjustment of the rate of feeding, and for the ready return of the carrier toward starting position, while minimizing the duration of contact 30 of the principal operating surfaces at each adjustment, thereby avoiding useless wear of the parts and friction, and better insuring accuracy of operation of the feeding mechanism at any of its adjustments. Other 35 objects, peculiar to the present invention, as well as in common with those of the patents mentioned, will appear in the course of the ensuing description.

I attain these objects by the device illustrated, for example, in the accompanying drawings, in which—

Figure 1 is a top plan view of the machine with part of the top broken away and omitted to reveal the interior details;

Fig. 2 is a left-end elevation with part of the casing end broken away and omitted to reveal the interior details;

Fig. 3 is an enlarged partial plan view corresponding to Fig. 1, partly in horizontal section on the plane of the line 3—3 of Fig. 2;

Fig. 4 is a partial front elevation of the

machine, on the scale of Fig. 3, with the front of the casing and other parts at the extreme front omitted to reveal the interior 55 details; and

Fig. 5 is a partial front-to-rear vertical cross-section on the plane of the line 5—5 of Fig. 4, better illustrating the shield and associated parts.

The base 1 is rectangular, supporting the casing 2 of similar shape with a removable top 3 having the cutter-bar 4 along its front edge. The top 5, which preferably is a slab of sanitary ware, such as porcelain, 65 enameled metal or the like, is set down in the top of the frame on suitable transverse supports 6 with cushioning material 7, such as rubber or the like, between the top 5 and these supports 6. This permits the ready 70 removal of the top 5 for access to the interior of the casing, or for cleaning the top and the adjacent parts of the frame.

The upper edges of the lateral sides of the casing 2 are recessed for most of their lengths, leaving the slots 8 under the edges of the top 5 and frame top 3. The rear part of the casing is lower than the top 5, and contains the cutter actuating mechanism comprising a sleeve 9 journaled in a bracket 10 and in the front end of the casing 2, outside which it carries a hollow arm 11 extending up with the cutter shaft 12 journaled in its upper end part and having fixed on said shaft the cutter 13 outside the 80 arm and the sprocket wheel 14 inside the arm. This arm also carries the guard 15 for the cutter 13, which is a dished disk swung very close to the cutter-bar 4 by this arm 11 while being rotated. This rotation is effected through a sprocket chain 16 passing around the wheel 14 and around a similar sprocket wheel 17 fixed on a shaft 18 inside the lower part of the arm 11; this shaft 18 being journaled concentrically 85 in the sleeve 9 and having fixed to it, outside the rear end of this sleeve 9, the bevel pinion 19 meshing with a bevel gear 20 fixed on the main driving shaft 21, which is journaled from front to rear in the casing 2, projecting out at the front with a hand-wheel 22 fixed thereon, having a handle 23 for driving the machine.

The swinging of the arm 11 is effected by

means of a fork 24 straddling and trunnioned on a collar 25 fixed to the sleeve 9, and a pin 24' slidable in this fork and pivoted to the side of a spur gear 26 turning 5 on a front-to-rear stud fixed in the front part of the casing. A spur pinion 27 on the main driving shaft 21 meshes with this spur gear 26, and may be fixed for rotation with the shaft 21 or released therefrom by 10 a stem 28 projecting out and having a knob 28' at the front of the hand-wheel 22, as fully set forth and claimed in my Patent No. 1,437,145 before mentioned. The above described cutter-driving mechanism is set 15 forth and claimed in my Patent No. 1,362, 855 before mentioned.

The carrier comprises a frame 29 of rectangular open formation, lying under the top 3, and guided on the frame of the 20 casing, where it has ears 30 extending out through the respective slots 8 at the front and rear sides of the casing 2. The ears 30 carry upright posts 31, on which is mounted a clamp or holder 32 (Figs. 1 and 2) for holding the article to be sliced, such as meat or the like, to be carried forward toward the cutter 13 by the carrier. This holder 25 comprises hooks or prongs 32' to engage down against the article, which is supported below by a transverse element 32'' connected to the posts 31 and slid along over the top 5 as fully disclosed in my prior 30 patents mentioned, or may be constructed otherwise as is well known in the art.

35 This carrier also comprises a bracket 33 extending down from its frame 29, with a front guide 34 slidingly embracing the screw 35 and a rear nut 36 meshing with the thread of this screw, which latter is journaled lengthwise of the machine in bearing bars 37 and 38 fixed inside the casing 2 near its top, at the front and rear ends, respectively.

40 This screw 35 is somewhat forward from the spur gear 26 that swings the cutter, and up from the center thereof, and has pinned on it the ratchet wheel 39 with teeth directed for driving the screw 35 over forwardly, which screw, having a right-hand 45 thread, drives the carrier to the left by virtue of the meshing of the nut 36 with the thread. The spur gear 26 has at its front, clamped around its hub by a set screw 40, a collar 41 on which is formed a cam 50 surface 42 along the front convex edge of a curved rib of the collar. The gear 26 rotating over to the left as the hand-wheel 22 is turned over to the right, this cam surface 42 is so formed that it has its advanced end inclining out from the gear, forward, at a less rate than its following end inclines in toward the gear; these oppositely inclined ends meeting in a curvature or convexity, as before alluded to.

55 A lever 43 has a fulcrum 44 in a rib ris-

ing from the base 1, just forward of the gear 26 and close to the left end of the casing; and this lever comprises a short lower forwardly extending arm 45 with a rounded front end engaging up against the bottom 60 of a plunger 46 sliding vertically in another rib of the base 1, directly under the screw 35 where it projects to its left end bearing bar 37. A tension spring 47 is stretched from the upper part of the plunger guiding rib down to the lower arm 45 of the lever 43; this spring holding the long upper arm 48 of the lever back toward the gear 26, where this arm has a roller 49 to bear against the cam surface 42 as the cam rib, passing 65 down at the left, pushes the lever arm 48 forward against the tension of the spring 47. This arm 48 projects up above the ratchet wheel 39, being suitably curved so that its upper end may swing back over the 70 gear 26 at the left thereof, and has pivoted to its upper end the link 50, extending forward close to the left end of the casing 2 and being pivoted to the upper end of the pawl arm 51 which turns loosely on the 75 screw 35 next to the bearing 37. A pawl 52 is pivoted on this pawl arm 51 and is held down, forward, against the ratchet wheel teeth by a small tension spring 53 stretched from the pawl down to the hub of the pawl 80 arm 51. The lever 43, as it is pushed forward by the cam surface 42, rotates the screw 35 until the cam surface passes the 85 pawl roller 49 and permits the lever to swing 90 backward under the action of the spring 47, 100 resetting the pawl on the ratchet teeth for the next stroke. Thus at each reciprocation of the pawl 52, the screw 35 is rotated through a partial revolution and advances the 95 carrier toward the cutter; the rate of this feeding being according to the effective 105 stroke of the pawl in engagement with the ratchet teeth.

110 I prefer to vary the effective action of the pawl on the ratchet wheel by two means, actuated in unison. Thus, a shield 54 is of disk shape, with a long hub 55 around the screw 35, and has its peripheral edge 56 at the left beveled; the hub 55 extending to the right and the ratchet wheel 39 being at the 115 left of the shield, toward which, along a part of its periphery, the shield has a segmental flange 57 projecting, interrupting the bevel of the edge and having its outer 120 peripheral surface continuous with the un-beveled part of the shield periphery. These peripheral surfaces are at such a radius that a roller 58, journaled on an extension of the pawl 52, riding up on and engaging with either one of these peripheral parts of the 125 shield, will lift the pawl 52 away from the ratchet wheel 39 and render the carrier feeding mechanism inoperative. This shield also carries, just at its left, the cam part 59, extending for about half the circumfer- 130

ence of the shield and having its periphery approximately spiral relatively to the shield axis; and this cam part 59 lies over and engages its peripheral edge with the upper end 5 of the plunger 46, so that as the shield 54 is rotated this spiral cam part 59 will stop the plunger 46, and consequently the backward swing of the ratchet-driving lever 43; earlier or later accordingly as a point of the 10 cam part at greater or lesser radial distance from the shield axis engages with the plunger.

This shield 54, in addition to being rotatable with respect to the screw 35, is slidable 15 therealong; the screw being reduced in diameter to receive this shield as well as the ratchet wheel and pawl arm, leaving a shoulder 60 at the right of the shield hub 55, which is engaged by the hub, stopping right- 20 hand sliding of the shield when this shield is pushed to the right by a spring 61 coiled around the screw 35 and compressed between the shield and the ratchet wheel 39. In this position, the shield has its flange 57 in the 25 path of the roller 58, to lift the pawl 52 away from the ratchet wheel; but the main peripheral part of the shield is out of reach of this roller unless the shield is pressed to the left, against the pressure of the spring 61, whereupon the roller 58 will pass out 30 upon this main part across the beveled edge 56 thereof. Preferably, the adjacent end 62 of the roller 58 also is beveled, to facilitate this passage of the roller axially onto 35 the shield periphery.

The carrier and its bracket 33 are so proportioned with respect to the cutter 13 and cutter-bar 4 that when the carrier has advanced the article far enough for the last 40 possible slice to be cut therefrom, the left end of the guide 34 of the carrier bracket pushes the shield 54 to the left by engagement with the right hand end of the shield hub 55.

For conveniently imparting to the shield 54 and its cam part 59 their rotary adjustment, and for holding them in their adjusted position, a bevel gear 63 is splined to the shield hub 55 by a key 64, and this gear 50 has its hub 65 journaled in a bracket 66 projecting back from the upper part of the front of the casing 2; being held by said bracket 66 against axial movement when the shield is moved axially. A bevel pinion 67 is fixed 55 on the rear end of a spindle 68 journaled horizontally through the casing front; this pinion meshing with the bevel gear 63, and the front end of the spindle 68, outside the casing, having fixed on it a knob 69 carrying a dial 70 with suitable graduations to 60 indicate, relatively to a fixed point on a boss 71 around the front of the spindle bearing, the degree of adjustment of the shield and its cam part. The pin which secures the bevel pinion 67 to its spindle is extended out

of the pinion hub, and a spring 72, coiled around the hub, is compressed between this pin and the rear of the spindle bearing; thus holding the dial 70 firmly back against the boss 71, so that, by virtue of the friction between the dial and boss, the shield and its cam part are held in their adjusted position. 70

The radius of the cam part 59 increases in direction opposite to that of turning of the screw 35; so that a rotation of the shield and this cam part oppositely to the rotation of the screw, swinging the flange 57 back from the pawl 52 and thus delaying the separation of the pawl from the ratchet 80 wheel 39, also accomplishes a recession of the cam part periphery from the plunger 46, permitting it to rise farther, and the lever 43 to swing back farther into the path of the cam surface 42, for effecting a longer stroke 85 of the pawl 52. Preferably, these parts are so proportioned that with any stroke afforded the pawl 52, the flange 57 will be at a point at which the pawl roller 58 will merely ride up onto the front end of the flange 57, ready to drop the pawl onto the ratchet teeth very early in the forward driving stroke, yet in such a secure position on the flange that the pawl will be held up thereby for permitting reverse turning of 90 the screw 35, by means of a crank 73 thereon outside the right or rear end of the casing 2, to run the carrier back to starting position after it has been fed forward and stopped automatically by its action on the shield as 95 before described, or at any other stage of 100 its feeding.

Operation.—The meat or other article to be sliced is secured in the holder 32 between its hooks 32' and lower element 32'' while the carrier is back at the right, to which position it is readily brought at any time except when the pawl 52 is forward off the shield flange 57 against the ratchet teeth. 105 As this engagement of the pawl exists only during the relatively short period when the cam surface 42, extending only a few degrees around the spur gear 26, is engaging with the lever roller 49, it will be seen that it seldom will interfere with running the carrier back manually by means of the crank 73; and then it is necessary only to turn the hand-wheel 22 a small fraction of a revolution to advance the cam surface 42 away 110 from the lever roller 49 and allow the pawl to ride back up on the shield flange 57. But at the next revolution of the gear 26, the pawl will engage and advance the carrier, with the article thereon, toward the cutter. 115 The screw 35 may be turned forward whatever the position of the pawl 52, so that, at the beginning, after placing the article on the carrier, it may be advanced manually until close to the cutter 13, ready to be sliced 120 at the first stroke of the cutter. Thus, the 125 130

forward or backward adjustment of the carrier for an article of any given length is readily accomplished without the aid of any special releasing device for the driving mechanism.

The machine now is ready for slicing from the article at any time; the thickness of the slices being readily adjusted simply by turning the knob 69 over to the right for reducing or over to the left for increasing the thickness of the slices. As this variation of the feed of the carrier is effected not only by moving the shield flange 57 forward or backward, but by reducing or increasing the permitted back swing of the lever 43 toward the cam surface 42, it will be seen that, with a reduced feed, the lever roller 49 is not permitted to engage with any more of the cam surface than is needed for the stroke required of the pawl for that feed, avoiding useless wear of these parts, and unnecessary resistance to operation of the machine. At the same time, by having the shield flange 57 to separate the pawl from the ratchet wheel 39 at the end of each backward stroke, the screw 35 always is released during most of each feeding and cutting cycle, for running the carrier back manually as just described. Also, by having the shield 57 adjusted proportionately with the pawl stroke, the pawl always reengages with the ratchet wheel very early in its forward stroke, before it gains momentum apt to throw it outward and cause incomplete engagement of the pawl with the ratchet tooth.

When the carrier has carried the article toward the cutter until the last slice is removed, the carrier bracket guide part 34, at the next turning of the screw 35 by the ratchet driving device, pushes the shield 54 toward the ratchet wheel 39 and forces the pawl away from the ratchet wheel by engagement of the beveled edge 56 with the pawl roller 58, so that the pawl will now travel idly, with the roller rolling on the main peripheral part of the shield 54, throughout the pawl stroke, so that the feeding device now is inoperative, although the hand-wheel continues to be turned by the operator.

By having the hub 41 that carries the cam surface 42 adjustable axially along the hub of the gear 26 by means of the clamping screw 40, the wear on the cam surface 42 and on the roller 49 and other parts of the feeding mechanism may be taken up, so that the feed may be maintained as originally designed, after the machine has been in use for a long period.

It will be noted that the axial movement of the shield 54 toward the ratchet wheel 39 is slight, relative to the diameter of the plunger 46 with which the cam part 59 of the shield engages, so that this cam part merely slides over a small portion of the top

of the plunger when the axial movement occurs, without deranging this part of the mechanism.

It will be seen that the automatic stoppage at the end of feeding is accomplished by simple means, of ample strength and durability, without complicating the adjustment for slices of different thicknesses, which may be accomplished either while the machine is running or while it is stopped, simply by turning the dial knob 69 one way or the other. Also, because the pawl is held up by the shield flange 57, the screw 35 is not turned forward upon adjusting from thicker to thinner slicing, which would result in a slice of abnormal thickness just after such adjustment in the absence of this provision.

Modifications of my invention may occur, and while I prefer certain details as disclosed, I do not wish to be understood as being limited to such precise disclosure, but having fully described my invention, I claim:

1. In combination, a carrier having a projecting member, feeding mechanism operatively related to said member comprising driving means rotary on an axis alined with said member, and means disposed entirely in alignment with said carrier member along said axis, whereby said carrier renders said feeding mechanism inoperative after a predetermined degree of feeding. 90

2. In combination, a carrier having a projecting member, feeding mechanism operatively related to said carrier member comprising a ratchet and a pawl driving said ratchet, and means disposed entirely between said carrier member and said pawl, forced by said carrier member directly into engagement with said pawl, to hold said pawl out of operative relation to said ratchet after a predetermined degree of feeding. 100

3. In combination, a carrier, feeding mechanism comprising a shaft having a threaded part engaging said carrier and a driving device for said shaft, and means movable axially on and embracing said shaft, forced by said carrier toward said driving device, whereby said carrier renders said driving device inoperative after a predetermined degree of feeding. 110

4. In combination, a carrier, feeding mechanism comprising a screw operatively related to said carrier and a driving device for said screw and means movable axially of said screw whereby said carrier renders said driving device inoperative after a predetermined degree of feeding, said means having another movement, and means whereby this other movement varies the rate of feeding of said carrier. 120

5. In combination, a carrier, feeding mechanism operatively related to said carrier comprising a ratchet member, a reciprocating pawl drivingly engaging said ratchet 130

- member, a shield to hold said pawl away from said ratchet member during a portion of the reciprocation of the pawl, and means to vary the stroke of the pawl and adjust 5 said shield along the stroke, in unison.
6. In combination, a carrier, feeding mechanism operatively related to said carrier comprising a ratchet member, a reciprocating pawl drivingly engaging said ratchet member, a shield having a part to hold said pawl away from said ratchet member during a portion of the reciprocation of the pawl, and means to vary the stroke of the pawl and adjust said shield along the stroke, in unison, 10 said shield being movable toward said pawl and having another part to hold said pawl away from said ratchet member throughout the stroke of the pawl, when said shield is moved toward said pawl.
- 15 7. In combination, a carrier, feeding mechanism operatively related to said carrier comprising a ratchet member, a reciprocating pawl drivingly engaging said ratchet member, a shield having a part to hold said pawl away from said ratchet member during a portion of the reciprocation of said pawl, means to vary the stroke of the pawl and adjust said shield along the stroke, in unison, 20 said shield being movable toward said pawl and having another part to hold the pawl away from said ratchet member throughout the stroke of the pawl, when said shield is moved toward said pawl, and means whereby said carrier moves said shield toward said pawl after a predetermined degree of feeding. 25
- 25 8. In combination, a carrier, feeding mechanism operatively related to said carrier comprising a rotary ratchet member, a reciprocating pawl drivingly engaging said ratchet member, a shield relatively to which said ratchet member rotates movable toward said pawl and having a part to hold said pawl away from said ratchet member throughout the stroke of the pawl, when said shield is moved toward said pawl.
- 30 9. In combination, a carrier, feeding mechanism operatively related to said carrier comprising a rotary ratchet member, a reciprocating pawl drivingly engaging said ratchet member, a shield relatively to which said ratchet member rotates, movable toward said pawl and having a part to hold said pawl away from said ratchet member throughout the stroke of the pawl, when said shield is moved toward said pawl, and means whereby said carrier moves said shield toward said pawl after a predetermined degree of feeding. 35
- 35 10. In combination, mechanism comprising a rotary member having a cam surface thereon, and a carrier, feeding mechanism operatively related to said carrier comprising means engaged by said cam surface for actuation of the feeding mechanism and means whereby said carrier renders said feeding mechanism inoperative after a predetermined degree of feeding, independently of the engagement of said cam surface. 40
- 40 11. In combination, mechanism comprising a rotary member having a cam surface thereon, and a carrier, feeding mechanism operatively related to said carrier comprising a ratchet member, a reciprocating pawl drivingly engaging said ratchet member, and means engaged by said cam surface for reciprocation of said pawl, a shield having a part to hold said pawl away from said ratchet member during a portion of the reciprocation of the pawl, means to limit the degree of engagement of said cam surface, to vary the stroke of the pawl, and to adjust said shield along the stroke, in unison, 45 said shield being movable toward said pawl and having another part to hold the pawl away from said ratchet member throughout the stroke of the pawl, when said shield is moved toward said pawl, and means whereby said carrier moves said shield toward said pawl after a predetermined degree of feeding. 50
- 45 12. In combination, mechanism comprising a rotary member having a cam surface thereon, and a carrier, feeding mechanism comprising a screw operatively related to said carrier, a ratchet wheel turning said screw, a pawl, mechanism actuated by engagement of said cam surface whereby said pawl turns said ratchet wheel and screw, and means for varyingly limiting said engagement of said cam surface to vary the stroke of said pawl. 55
- 50 13. In combination, mechanism comprising a rotary member having a cam surface thereon, and a carrier, feeding mechanism comprising a screw operatively related to said carrier, a ratchet wheel turning said screw, a pawl, mechanism actuated by engagement of said cam surface whereby said pawl turns said ratchet wheel and screw, a shield adjustable around said ratchet wheel to hold said pawl away from said ratchet wheel during a portion of the stroke of said pawl, and means for varyingly limiting said engagement of said cam surface to vary the stroke of the pawl. 60
- 55 14. In combination, mechanism comprising a rotary member having a cam surface thereon, and a carrier, feeding mechanism comprising a screw operatively related to said carrier, a ratchet wheel turning said screw, a pawl, mechanism actuated by engagement of said cam surface whereby said pawl turns said ratchet wheel and screw, a shield adjustable around said ratchet wheel to hold said pawl away from said ratchet wheel during a portion of the stroke of said pawl, and means actuated in unison with the adjustment of said shield for varyingly limiting said engagement of said cam surface to vary the stroke of the pawl. 65

15. In combination, a carrier, feeding mechanism operatively related to said carrier comprising a ratchet wheel, a reciprocating pawl drivingly engaging said ratchet wheel, a shield to hold said pawl away from said ratchet wheel during a portion of the reciprocation of the pawl, said shield being rotatable around said ratchet wheel, a bevel gear with which said shield is rotatable, and 10 a bevel pinon meshing with said bevel gear.

16. In combination, a carrier, feeding mechanism operatively related to said carrier comprising a ratchet wheel, a reciprocating pawl drivingly engaging said ratchet wheel, and a shield to hold said pawl away from said ratchet wheel during a portion of the reciprocation of said pawl, said shield being rotatable around said ratchet wheel and being movable axially and having a part 20 to hold said pawl away from said ratchet wheel throughout the stroke of the pawl, upon movement of said shield axially in one direction.

17. In combination with a support, and a carrier, feeding mechanism operatively related to said carrier comprising a ratchet wheel, a reciprocating pawl drivingly engaging said ratchet wheel, a shield to hold said pawl away from said ratchet wheel during a portion of the reciprocation of said pawl, said shield being rotatably around said ratchet wheel and being movable axially and having a part to hold said pawl away from said ratchet wheel throughout the stroke of the pawl, upon movement of said shield axially in one direction, a bevel gear with 30 which said shield is rotatable but which permits axial movement of the shield relatively to the gear, a bevel pinon meshing with said bevel gear, and fixed bearings for said gear and pinon on said support.

18. In combination, a carrier, feeding mechanism operatively related to said carrier comprising a ratchet wheel, a reciprocating pawl drivingly engaging said ratchet wheel, a shield to hold said pawl away from said ratchet wheel during a portion of the reciprocation of the pawl, said shield being rotatable around said ratchet wheel and being movable axially and having a part to hold said pawl away from said ratchet wheel throughout the stroke of the pawl, upon movement of said shield axially in one direction, said shield having an extension engaged by said carrier to cause the axial movement of said shield.

19. In combination with a support, and a carrier, feeding mechanism operatively related to said carrier comprising a ratchet wheel, a reciprocating pawl drivingly engaging said ratchet wheel, a shield to hold said pawl away from said ratchet wheel during a portion of the reciprocation of said pawl, said shield being rotatable around said ratchet wheel and being movable axially and

having a part to hold said pawl away from said ratchet wheel throughout the stroke of the pawl, upon movement of said shield axially in one direction, a bevel gear with which said shield is rotatable but which permits axial movement of the shield relatively to the gear, a bevel pinon meshing with said bevel gear, and fixed bearings for said gear and pinon on said support, said shield having an extension engaged by said carrier to cause the axial movement of said shield.

20. In combination, mechanism comprising a rotary member having a cam surface thereon, and a carrier, feeding mechanism comprising a screw operatively related to said carrier, a ratchet wheel turning said screw, a pawl, mechanism actuated by engagement of said cam surface whereby said pawl turns said ratchet wheel and screw, a shield adjustable around said ratchet wheel to hold said pawl away from said ratchet wheel during a portion of the stroke of the pawl, a stop cam adjustable with said shield, and means whereby said stop cam varyingly limits said engagement of said cam surface to vary the stroke of the pawl.

21. In combination, mechanism comprising a rotary member having a cam surface thereon, and a carrier, feeding mechanism comprising a screw operatively related to said carrier, a ratchet wheel turning said screw, a pawl, a lever having an arm carrying said pawl and engaged by said cam surface and having another arm, a plunger against said other arm, a spring engaging said lever to move the lever toward said cam surface to be moved thereby in opposition to said spring whereby said pawl turns said ratchet wheel and screw, a shield adjustable around said ratchet wheel to hold said pawl away from said ratchet wheel during a portion of the stroke of the pawl, and a stop cam adjustable with said shield and engaging said plunger to limit movement of said lever toward said cam surface of said rotary member.

22. In combination, a carrier, feeding mechanism operatively related to said carrier comprising a ratchet wheel, a reciprocating pawl drivingly engaging said ratchet wheel, a shield adjacent to said ratchet wheel, a roller on said pawl engaging with one part of said shield to hold said pawl away from said ratchet wheel during a portion of the stroke of the pawl, said shield being movable axially toward said ratchet wheel and having another part of extent to hold said pawl away from said ratchet wheel throughout the stroke of the pawl, and said roller having a receding edge whereby said roller passes onto said other part of the shield upon movement thereof axially toward said ratchet wheel.

23. A ratchet shield comprising a disk

having a beveled peripheral edge and having an axially extended flange along a part of its peripheral edge.

24. A ratchet shield comprising a disk having a beveled peripheral edge, and having an axially extended flange along a part of its peripheral edge, and having a cam part spaced axially beyond said beveled edge from said flange.

10 25. A ratchet shield comprising a disk having a beveled peripheral edge, and having an axially extended flange along a part of its peripheral edge, and having a hub extending axially beyond said beveled edge from said flange.

15 26. A ratchet shield comprising a disk having a beveled peripheral edge, and having an axially extended flange along a part of its peripheral edge, and having a hub extending axially beyond said beveled edge from said flange, and having a cam part between said beveled edge and said hub, spaced toward said hub away from said beveled edge.

20 27. In combination, a ratchet wheel, a pawl, a roller on said pawl extending past one side of the ratchet wheel and having its extended edge beveled, and a shield comprising a disk having a beveled peripheral edge and having an axially extending flange along a part of its peripheral edge in the path of said roller as it travels with said pawl, adapted to hold said pawl away from the ratchet wheel when engaged by said 25 roller, and said shield being movable toward said ratchet wheel to move said pawl away from said ratchet wheel when said beveled edge of said shield engages said beveled edge of said roller.

28. In combination with a carrier, mechanism comprising a rotary member having a hub, and feeding mechanism for said carrier comprising a member clamped on said hub for adjustment axially therealong, and means engaging with said member to be 45 operated thereby, the wear of which is taken up by said adjustment.

29. In combination, a support having a top with a recess throughout its major extent, and a removable top member lying in said recess, a carrier extending above and below said top member to carry an article along the upper surface of said top member, a cutter toward which the article is carried by said carrier, operating mechanism for said cutter, and feeding mechanism for said carrier, below said top and operatively connected to said carrier therebelow, the removal of said top member affording access to said mechanisms, said top member lying loosely in said recess, and cushioning material supporting said top member in said recess.

30. In combination, a carrier, and feeding mechanism comprising a screw operatively related to said carrier and a ratchet driving device for said screw, and shield means whereby said carrier renders said driving device inoperative after a predetermined degree of feeding but whereby said screw continues to be operatively related to said carrier, said shield means being adapted to maintain said ratchet device inoperative during return of the carrier to starting position by rotation of said screw in reverse direction.
